UNITED STATES PATENT OFFICE.

THOMAS F. HATHAWAY, OF ELGIN, ILLINOIS, ASSIGNOR TO ILLINOIS WATCH CASE COMPANY, OF ELGIN, ILLINOIS, A CORPORATION OF ILLINOIS.

CASE FOR CIGARETTES AND THE LIKE.

1,279,339.

Specification of Letters Patent. Patented Sept. 17, 1918.

Application filed June 21, 1918. Serial No. 241,151.

To all whom it may concern:

Be it known that I, THOMAS F. HATHAWAY, a citizen of the United States, residing at Elgin, in the county of Kane and State of Illinois, have invented certain new and useful Improvements in Cases for Cigarettes and the like, of which the following is a specification.

The present invention has to do with cases of the kind which make use of a holder mounted between the covers of the case, and is more especially concerned with a certain novel improvement and arrangement of parts by which a number of articles are firmly held within the holder, which in turn is maintained in a central position between the covers of the case.

In carrying out this invention I have aimed to simplify as much as possible the construction of the case, to eliminate all unnecessary parts, and to attain the desired results by means which are part positively and part spring actuated. With these and other ends in view, as will more fully hereinafter appear, an understanding of my invention may be gained by reference to the accompanying drawing, wherein is shown a preferred embodiment thereof, and in which:—

Figure 1 is a longitudinal section through one of the covers of the case as it appears when opened, the holder being shown in elevation;

Fig. 2 is an enlarged fragmentary plan view of the hinged edges of the covers, the two sections of the holder being spread apart for purposes of illustration;

Fig. 3 is a detail in perspective of the inter-locking connection between a joint of one cover and a joint of one holder section;

Figs. 4 and 5 are details in cross section taken respectively on lines 4—4 and 5—5 of Fig. 2.

As is usual with cases of the general kind to which this invention relates, use is made of two dished covers 6 and 7 hinged together by means of a pintle 8 which extends through a number of joints 9 and 10 formed along the edges of the covers 6 and 7 respectively. If desired, the backs of the two covers adjacent to their hinged connection may be formed to abut when the case is opened to the desired extent, the device illustrated in the drawings being so constructed and hav-

ing the opening movement of its covers 55 thereby limited to about 180°.

Mounted within the case is a swinging holder consisting of two sections 11 and 12 formed with joints 13 and 14 respectively, which are alined with the cover joints 9 and 10 so that the pintle 8 may pass through them all, thus forming a common and coaxial hinged connection between the two covers of the case and the two sections of the holder. Each section is appropriately 65 fluted or otherwise shaped to accommodate conveniently its intended contents, the holder illustrated being designed for the reception of cigarettes.

One joint 14 of the holder section 12 is 70 specially constructed by having its portion encircling the pintle 8 partially cut away as at 15 to provide a stop or abutment 16, which co-operates with a stop or abutment 17 similarly formed on the adjacent 75 joint 10 which is connected with the cover 7, being the cover adjacent to the holder section 12. These two joints may be termed interlocking, since the stops lock with each other when the holder section 12 has swung 80 through a predetermined distance away from its proximate cover 7 toward the opposite or remote cover 6.

In the construction illustrated, it will be noted that this interlock affects only the 85 holder section 12 and the cover 7 adjacent thereto, and, furthermore, is operative only when the holder section approaches a position substantially perpendicular thereto. Now similar interlocking stops are provided 90 on the other holder section 11 and the cover 6 adjacent thereto, the numerals 15^a, 16^a, and 17^a designating the parts thereof which correspond respectively to the parts 15, 16, and 17 already described. The effect 95 of these two sets of interlocking stops is to positively prevent the two holder sections from swinging past the center position between the covers when the case is fully opened. This centralizing action of these 100 interlocking joints is not completely effective, however, except when the covers are opened to their limit, as in all other angular positions of the covers the engaging stops or abutments of each interlock remain apart 105 sufficiently to allow a certain amount of idle swinging movement of each holder section between the two covers, the extent of such

swinging movement, of course, varying according to the positions of the covers relative to each other. When, however, the case is fully opened, the cover joints interlock 5 with those of the holder sections so as to bring the two sections of the holder together in a position centrally of the case, and this action has the effect of limiting the swinging of the covers as well. This means of 10 determining the extent to which the covers may open is preferably ancillary to that provided in the cover backs, which I have already stated are preferably so constructed as to abut when the desired degree of opening 15 has been reached; but it should be understood that either means, or both acting together, may be employed for this purpose.

The case thus far described comprises two 20 covers and two holder sections all co-axially pivoted and equipped with means to centralize the holder sections when the covers are fully opened. I make use of other means, however, for normally causing the 25 covers to open and for maintaining the two holder sections together under tension so as to exert a gripping effect upon the articles contained therein, regardless of the angular position of the holder between the covers. 30 For this purpose two springs are used, each coiled around the pintle 8. One of these springs, designated as 19, has its ends 20 and 21 bearing down upon the covers 6 and 7 respectively (see Fig. 5) so as to exert 35 an opening influence upon them. This is the only function of the spring 19. The ends 22 and 23 of the other spring 24 are turned up so as to engage respectively the holder sections 11 and 12 in a manner tending 40 to press them together, and this is the only purpose subserved by the spring 24.

It will be observed that the purposes of 45 opening the covers, centralizing the holder, and pressing the holder sections together, 50 are accomplished by three separate means, namely, the ends of the spring 19, the oppositely acting interlocking joints, and the ends of the spring 24, respectively. The arrangement is such, however, that all three 55 act simultaneously and with certainty to subserv their intended functions. The action of the spring 24 tends to maintain the holder sections in closed relation, to constitute, in effect, a unitary holder, and this 60 spring action complements that of the interlocking joints in maintaining the holder, as a unit, in centralized position, since any de-

flection of either of the holder sections from its central position is resisted on the one side by the action of the stops composing the 60 interlocking joints, and on the other side by the complementary action of the spring. The spring thus serves to unite the holder sections so that their movement in either direction will be equally resisted. 65

I claim:

1. In a case of the kind described, the combination of two covers and two holder sections therebetween all pivotally connected to swing about a common axis, co-operating 70 means on each cover and the adjacent holder section for limiting the swing of each holder section away from its adjacent cover to a point substantially centrally of the covers when the case is opened to a predetermined 75 point, tension means for opening the covers, and other tension means for maintaining the holder sections together in unitary relation, substantially as described.

2. In a case of the kind described, the combination of two covers, each formed with joints and having a pintle extending therethrough to form a hinge connection between the covers, two holder sections between the covers, each formed with joints 85 aligned with those on the covers, whereby the pintle provides a common hinge connection, a torsional spring coiled around the pintle and having its ends bearing upon the covers to open them, a second torsional 90 spring coiled around the pintle and having its ends bearing against the holder sections to maintain them together in unitary relation, and means formed on each cover co-operating with other means formed on the 95 holder sections for centralizing the holder when the case is opened, substantially as described.

3. In a case of the kind described, the combination of two covers and two holder 100 sections therebetween all formed with joints and having a pintle extending therethrough to form a common hinge connection, one joint on each cover being adapted to co-operate with one joint on the holder section adjacent thereto to limit the distance that said section may swing away from its adjacent cover, tension means for normally holding the holder section together in unitary relation, and other tension means acting solely to open the covers, substantially 105 as described.

THOMAS F. HATHAWAY.
